US00D774791S

(12) **United States Design Patent** (10) **Patent No.:** **US D774,791 S**
Toll (45) **Date of Patent:** **** Dec. 27, 2016**

(54) **BICYCLE SEAT**

(71) Applicant: **TAMPA BAY RECREATION, LLC**,
Lutz, FL (US)

(72) Inventor: **Steven G. Toll**, Tampa, FL (US)

(73) Assignee: **ISM Saddles, LLC**, Lutz, FL (US)

(**) Term: **15 Years**

(21) Appl. No.: **29/539,813**

(22) Filed: **Sep. 17, 2015**

(74) *Attorney, Agent, or Firm* — Akerman LLP; Peter A. Chiabotti

(57) **CLAIM**

The ornamental design for a bicycle seat, as shown and described.

DESCRIPTION

FIG. 1 is a perspective view of the ornamental design; FIG. 2 is a top plan view of the ornamental design of FIG. 1;

FIG. 3 is a bottom plan view of the ornamental design of FIG. 1;

FIG. 4 is a left side elevation view of the ornamental design of FIG. 1;

FIG. 5 is a right side elevation view of the ornamental design of FIG. 1;

FIG. 6 is a front view of the ornamental design of FIG. 1;

FIG. 7 is a rear view of the ornamental design of FIG. 1;

FIG. 8 is a perspective view of an alternative embodiment of the ornamental design of FIG. 1;

FIG. 9 is a top plan view of the ornamental design of FIG. 8;

FIG. 10 is a bottom plan view of the ornamental design of FIG. 8;

FIG. 11 is a left side elevation view of the ornamental design of FIG. 8;

FIG. 12 is a right side elevation view of the ornamental design of FIG. 8;

FIG. 13 is a front view of the ornamental design of FIG. 8; and,

FIG. 14 is a rear view of the ornamental design of FIG. 8.

1 Claim, 10 Drawing Sheets
